UNITED STATES PATENT OFFICE.

CHARLES H. MORGAN, OF WORCESTER, MASSACHUSETTS.

WIRE-ROD-ROLLING MILL.

SPECIFICATION forming part of Letters Patent No. 334,454, dated January 19, 1886.

Application filed November 28, 1885. Serial No. 184,200. (No model.)

To all whom it may concern.

Be it known that I, CHARLES H. MORGAN, of Worcester, in the county of Worcester and State of Massachusetts, have invented certain new and useful Improvements in Wire Rod-Rolling Mills; and I do hereby declare that the following is a full, clear, and exact description of the same, reference being had to the accompanying drawings, forming a part of this specification, and in which—

Figure 1 represents a top or plan view of my improved rolling-mill; and Fig. 2, a vertical longitudinal section of the same, taken on the line A B, Fig. 1, looking in the direction indicated by the arrow, same figure, also showing parts of the mill in side view.

My invention relates to rolling-mills for rolling wire rods directly from fluid or molten metal; and it consists in the combination, with a continuous train of reducing-rolls, of a suitable apparatus for reducing scrap or pig iron to a molten state, refining the same, then conducting said molten metal to a pair of cooling and forming rolls, thence to the reducing-rolls aforesaid, said metal being cooled to a temperature just below a molten state in any suitable manner prior to entering the forming-rolls above referred to, cut apart as required after leaving said forming-rolls and prior to entering the reducing-rolls, and the waste caught underneath by suitable means, herein-after more fully described.

It also consists in the combination of the parts aforesaid with suitable reeling devices, conducting-pipes, and one or more supplementary sets of reducing-rolls, substantially as hereinafter set forth.

In the accompanying sheets of drawings, Figure 1 shows a plan view. Fig. 2 shows a side view, partly in section.

In the drawings, C represents an ordinary train of reducing-rolls, provided with the usual guides, C', for conducting the rods from one set of reducing-rolls to another in the process of reduction.

The part marked D represents an ordinary cupola, provided with the usual means for melting the scrap or pig iron contained therein, and with the outlet D' at the bottom, for "tapping" said molten metal when required for use, as hereinafter described.

E represents a crane, having an ordinary Bessemer converter, E', mounted upon the

outer end of its swinging arm E², and made hollow for conducting an air-blast to said converter, said arm also being fitted to turn on its bearings, and provided with means whereby said arm and its converter are turned when required, as hereinafter more fully explained. The purpose of said crane and converter is to transfer the molten metal in the cupola D to the receiving-ladle F, being refined in said converter by the usual Bessemer process. The upper part, a, of the crane E is fitted to slide up and down in the frame or base b, being operated by turning the hand-crank c by means of the usual mechanism contained within said vertical base part b. Said parts a and b are so constructed as to admit of the passage of the air-blast hereinbefore referred to up through the crane to the converter E' thereof. The part a not only moves vertically, but also turns in its bearing, so that the arm E² may be swung around to conduct the converter from the cupola D to the receiving-ladle F, and vice versa, as required in transferring the molten metal from the former to the latter. The converter is tipped, as required in performing said operation, by means of a hand-crank, g, through the crank-shaft h, turning in suitable bearings, and provided at its upper end with the threaded part h', which meshes with the worm-gear i on the arm to which said converter is attached. The receiving-ladle F is provided at the bottom with a suitable outlet and tube, j, converging inward toward the bottom, through which the metal passes prior to entering the forming-rolls k k, arranged to turn just under the same.

In order that the molten metal contained in the ladle F may be cooled sufficiently to mold the same in passing between the forming-rolls k, and yet not unduly retard its progress downward through the tunnel-shaped tube j, I arrange a suitable number of pipe-coils, l, around the same, through which may be passed a current of cold water or a steam-blast, applied in any suitable manner. I do not limit myself, however, to this method of cooling, as various ways may be adopted to effect the same result.

The temperature of the metal in the receiving-ladle F is maintained and controlled by applying a hot-blast to the top thereof, produced by the use of petroleum or other hydrocarbon, forced through the blast-pipe

m and into said metal by means of superheated steam or air.

Previous to pouring the first charge from the converter *E* into the ladle *F* the bottom opening of said ladle is closed by means of a plug, *n*, operated by a rod extending up therefrom. The ladle having been filled, said plug is then withdrawn, thus allowing the metal to flow down through the tube *j* and between 5 the rolls *k k* into the receptacle *p*. When the metal has arrived at the proper consistency to pass it into the continuous train *C*, it is cut apart, as it continues to flow down, by means of a suitable cutting device arranged 10 under the forming-rolls *k k*, the free end being then caught by an attendant, by means of suitable tongs, and fed in between the first set of reducing-rolls of the continuous train *C*, which then carries it along through the different stages of reduction in the usual way. 15 In this instance I cut the metal apart, as aforesaid, by means of the rotating cutters *o*, having the cutting-edges *o'*, which, when they come together by the rotation of said cutters, act as 20 shears to sever the metal. Said cutters may be operated, as required, by any suitable and convenient means. As the metal leaves the last set of rolls of the continuous train *C*, it enters and passes through a stationary conducting-pipe, *H*, thence into and through a 25 rotating pipe, *H'*, and is distributed in the stationary reel *G* around the central cone, *G'*, thereof. Said reel is arranged in a suitable 30 inclosure of fire-brick, in which a fire may be kept up, if necessary, to maintain or increase the temperature of the metal deposited in 35 said reel as aforesaid.

The distributing-pipe *H'* is operated by a driving-shaft, *I*, (driven by any suitable 40 means,) through the spur-gears *I* and *I'*, which work together, the pipe *H'* being arranged in the gear *I*, and both of said gears fitted to turn in the frame *J*.

If desired, the rods deposited in the reel *G* 45 may be still further reduced in size by passing them through one or more sets of supplementary rolls, *C'*. In removing the same from the reel one end of the rod is drawn up through the central opening in the gear *I*, (the 50 pipe *H'* having been previously removed,) and thence over the friction-roll *q* to said supplementary rolls. The friction-roll *q* is fitted to turn in a suitable bearing, *r*, which may in turn be fitted to rotate, if desired, to facilitate 55 said drawing-off operation.

It will be understood that the rolls *k* and those of the continuous train *C* are constructed and fitted to turn in the usual well-known manner, also being operated by ordinary 60 mechanism connected therewith.

In the foregoing specification I have described only one reel, crane, and cupola; but, if desired, two of each may be employed, and the other parts made to correspond therewith, 65 as shown in Fig. 1, thereby increasing the production of my improved mill.

By the use of two cranes and converters working alternately the receiving-ladle *F* and continuous mill may be kept in constant operation, as will be readily seen, the rods being directed to first one reel and then the other as fast as delivered from said mill, and subsequently drawn off, with less haste, to the supplementary rolls, as hereinbefore described.

7c

In practice I propose to use a suitable switch device for directing the rods into first one and then the other of the conducting-pipes *H* as they leave the continuous train *C*.

Although I have shown only two reeling 80 devices in this instance, a greater number may be used, if desired, without departing from the principle of my invention.

Having described my improvements in rolling-mills, what I claim therein as new 85 and of my invention, and desire to secure by Letters Patent, is—

1. The combination of a continuous train of reducing rolls with the means for reducing scrap or pig iron to a molten state, for conducting said molten metal to a suitable receiving-ladle and refining the same during the transit thereof, for conducting the metal from said receiving-ladle to and between suitable forming-rolls, and for cutting said metal 95 apart preparatory to its being fed into the first set of rolls of the aforesaid continuous train of rolls, substantially as and for the purposes set forth.

2. The combination of the continuous train 100 of rolls *C* with the cutters *o*, forming-rolls *k k*, receiving-ladle *F*, means for supporting said ladle, and means for supplying the same with molten metal, for conducting said metal to the rolls *k k* aforesaid, and for controlling 105 the discharge and temperature thereof, substantially as and for the purposes set forth.

3. The combination of the reeling mechanism, constructed and arranged substantially 110 as described, and the continuous train of rolls *C* with the cutters *o*, forming-rolls *k k*, receiving-ladle *F*, means for supporting said ladle, and means for supplying the same with molten metal, for conducting said metal to the rolls *k k* aforesaid, and for controlling the discharge 115 and temperature thereof, substantially as and for the purposes set forth.

4. The combination of one or more sets of supplementary rolls, the reeling mechanism, constructed and arranged substantially as described, and the continuous train of rolls *C* with the cutters *o*, forming-rolls *k k*, receiving-ladle *F*, means for supporting the same, and means for supplying it with molten metal, for conducting said metal to the rolls *k k* aforesaid, 120 and for controlling the discharge and temperature thereof, substantially as and for the purposes set forth.

CHAS. H. MORGAN.
